UNITED STATES PATENT OFFICE

2,526,363

SAFETY DEVICE FOR VAPOORIZER SYSTEMS

Sam P. Jones, Dallas, Tex.

Application April 5, 1946, Serial No. 659,826

13 Claims. (Cl. 62—1)

1

The present invention relates to a safety device for vaporizer systems, and has particular application to those systems wherein a liquefied gas, such as propane or butane, is vaporized for use as a heating and power generating fuel. The invention is concerned with valve means for controlling the flow of either liquid or vapor, or both, between a vaporizer chamber and a supply tank, which valve means cannot be inadvertently operated. Furthermore, the valve means may be operated automatically in response to excess temperature conditions, such as those caused by the presence of flame.

This mechanism is particularly applicable to a vaporizer system of the back-pressure, backflow type, having a vaporizer column, chamber, or standpipe disposed adjacent the fuel supply tank and connected thereto by a liquid passage between the bottom of the vaporizer column and the bottom of the liquid tank, and a vapor passage connecting the top of the vaporizer column and the top of the tank, so that the liquid assumes its level in the vaporizer column. It is desirable to be able to control the flow in both of the two connecting lines. However, difficulties have arisen because, when conventional valves are provided in these lines, they may be operated inadvertently or at the wrong time, leading to serious trouble.

It is an object of the invention to provide controls for each of the two connecting lines mentioned, which cannot be inadvertently operated. A further object is to provide valve controls in these lines that can be operated only by a particular sequence of operations on the part of a person in control of the system. Another object is to provide valves that can be operated only by an enclosed operating means. A further object is to provide a control of this kind which will afford automatic operation in the event of fire or excess heat. A further object is to provide controls of this kind that will operate quickly and easily whenever shutting off of the valves is desired.

Other objects will appear from the description to follow.

In the drawings:

Fig. 1 is a side elevation of a vaporizer system in which the present invention is embodied;

Fig. 2 is an enlargement of the mechanism shown in Fig. 1 with the housing cut away and parts shown in section;

Fig. 3 is a vertical section through one of the valve devices, with the valve closed;

2

Fig. 4 is a view similar to Fig. 3, but with the valve shown in open position;

Fig. 5 is a similar view of the valve but taken at 90° to the view of Fig. 3.

5 Fig. 6 is a transverse section, taken on the line 6—6 of Fig. 3.

The vaporizer mechanism is adapted to be used in connection with a storage tank 10 for containing liquid such as propane or butane or mixtures of these, or other like volatile liquids. Associated with the tank 10 is a vaporizer column, generally indicated at 11 and being, with its associated accessories, contained within a housing 12. The column is, of course, hollow and is connected at its bottom end to the bottom of the tank 10 by a liquid line 13. It is also connected at its top end by a vapor line 14. By these means, the liquid level within the tank 10 may find its equal in the column 11.

10 20 In this type of vaporizer system, the pressure above the liquid in the column 11 regulates the height of liquid in the column, and, by this latter, determines the rate of vapor generation. This is accomplished by having heating means located at the bottom of the column, which heating means heats the bottom of the column in maximum amount, with decreasing heating of the column upwardly from the bottom. Variation in the height of liquid level in the column, therefore, 15 varies the amount of liquid in contact with the hot parts of the column.

25 The system, to accomplish the foregoing, has a cap 18 at its top, which receives the vapor line 14, and also receives the connections for a service line 19 to carry the vaporized liquid off to the burner, engine, or other consuming apparatus. The line 19 connects through a valve 20 and a pressure regulator 21. It finally leads into a 30 T 22, from which a vapor outlet line 23 leads to the consuming apparatus. From the T, another line 25 extends to a valve mechanism 26. From this mechanism, another line 27 leads to a series of controls, generally indicated at 30, and which provide a controlled main burner 31 and a pilot burner 32 disposed adjacent the bottom of the column 11. The main burner 31 is designed to heat the bottom of the column to vaporize the liquid therein. The bottom of the column is enclosed within a heat-containing casing 33.

35 40 45 The foregoing mechanism need not be described in detail because it is set forth in a copending application of this applicant, Serial No. 643,821, filed January 26, 1946. It will be understood that, when vapor is initially required by the consuming line 23, it is drawn off from the top of

50 55

the column 11 above the liquid therein. If this does not supply an adequate amount of vapor, additional vapor will be drawn off from the top of the tank 10. Suitable pressure differential flow control and check valves are ordinarily used in the line 14 to regulate this latter. They are omitted here for clarity because they form no part of the present invention.

Some of the gas that is drawn off is returned to the burners 31 and 32 which operate to provide heat to the bottom of the column, which heat, acting upon the liquid contained within the column, vaporizes the liquid and supplies the quantity of gas desired. The capacity of the burner for the generation of gas is usually greater than the maximum possible demand. Hence, when the burner goes into full operation, after a demand has been started, the amount of generation will be greater than the demand and, as a result, the pressure above the liquid in the column 11 will begin to rise and will exceed the pressure acting on the top of the liquid in the tank 10. This will depress the level of the liquid within the column 11 and force it back through the line 13 into the tank 10. In so doing, the amount of liquid in contact with the heated parts of the column 11 will decrease and, as a result, the amount of gas generated will likewise decrease. In the foregoing manner, an equilibrium will be established wherein the amount of gas generated equals the demand and wherein the liquid level is at a proper point to effect the correct amount of gas generation.

It is fairly evident that there are times when it is desirable and necessary to control the flow of liquid and gas in the two lines 13 and 14. For example, when the vaporizer column is repaired or replaced, it is necessary to have some way to prevent the escape of all of the liquid within the tank 10 at the time the line 13 is disconnected from the bottom of the column 11. Also, in the event a gas leak develops in the vaporizer column, or its associated mechanism enclosed within the housing 12, it is desirable to have some way to stop the gas generation. This is particularly true because the escaping gas may become ignited within the housing 12 owing to the presence of flame at the main or pilot burner, and such flame creates a serious hazard. However, without some way to stop the generation of gas, there is no way to stop the flame until all of the fuel in the tank 10 is consumed.

On the other hand, if conventional manual valves are provided in the lines 13 and 14, they might both be closed, inadvertently or otherwise, while gas is going into the consuming appliances, such as heaters or stoves. As soon as the valves are shut off, the gas flow to the consuming apparatus would cease, although the burner valves would still be open. Then, if the hand valves are again opened, immediately gas would flow to the housing through the open valves and would escape into the rooms without being ignited. This, of course, creates a very serious fire hazard.

Also, a valve in the liquid line 13 should not be capable of being inadvertently or intentionally closed at the time the vaporizer column is seeking to establish an equilibrium between the amount of gas generated and the consumption. This establishment of equilibrium requires the free ability of the liquid to flow back and forth through the line 13 between the tank 10 and the column 11, as otherwise the liquid level of equilibrium in the column 11 cannot be established. If the valve be closed at the time the

consumption is less than the generation, serious excessive pressures may be produced in the column 11.

The present invention provides the control of these lines that is desirable and at times necessary, and yet avoids the hazards that come from the use of conventional manual valves, or the like. To this end, it employs a valve 40 in the liquid line 13 and a valve 41 in the vapor line 14. These two valves are identical so that only one need be described in detail. The valve 41 is shown in Figs. 3 to 6.

It will be seen that the tank 10 is provided with a nipple 42 that receives the externally threaded shank 43 on a valve housing 44. The shank 43 is provided with an internal inlet passage 45 that is internally threaded at its outer end to receive threaded discs 46 and 47, duly ported so that liquid or vapor may flow past both of the discs. The two discs provide between them a chamber 48 that may receive an excess flow control valve of conventional type, which is not shown for purposes of clarity.

The upper end of the passage 45 is reduced in diameter to provide a valve seat 50. Beyond the valve seat, the passage continues at 51 into a transverse passage 52 that leads to the line 14.

A continuation of the passage 51 is provided at 54 on the opposite side of the outlet passage 52. This passage 54 opens into a recess 55 that forms one side of a diaphragm chamber.

A diaphragm 56 is disposed across the outer surface of the valve housing member 44 and is clamped thereto by a cover 58, which has a recess 59 that is complementary to the recess 55, both of these recesses providing space for the operation of the diaphragm.

Below the diaphragm is a valve member, generally indicated at 60. This valve member includes a valve head 61 that is located in the inlet passage 45. Preferably, the head 61 is hexagonal or some other non-circular shape, so that it is centered within the circular passage 45 but provides for the flow of gas around it. The head 61 has a valve closing portion 62 thereon that may seat on the valve seat 50 to check the flow between the inlet 45 and the outlet 52, with washers as desired. The valve head 61 is connected to a button 64 by a stem 65. The button 64 reciprocates and is guided in the passage 54, and also engages against the under side of the diaphragm 56. It is urged into contact with the diaphragm 56 by a coil spring 66 that acts between the upper washer disc 47 and the valve head 61. The spring 66 preferably seats in a recess within the valve head so that it is properly confined.

The valve cap 58 has a slot 70 extending inwardly from one end to receive one end of a bell crank lever 71 that is pivoted to the cap at 72. One arm 73 of the bell crank lever operates in the slot 70 and is adapted to engage a button 74, having a baffle plate 75 that operates against the top of the diaphragm 56. The button 74 is reciprocable within a circular opening 77, and is thereby guided.

The other arm 78 of the bell crank lever receives one end of a cable 80.

It will be seen that the valve is normally closed under the action of the coil spring 66 when the bell crank lever 71 is released. This position is shown in Fig. 3. When, however, the arm 78 of the bell crank 71 is pulled by the cable 80, the bell crank is rocked about its pivot 72, and its other arm 73 depresses the button 74 which

acts upon the top of the diaphragm 56, and this, in turn, causes the button 64 of the valve to be depressed against the coil spring 65 and to be opened, permitting flow from the inlet 45 to the outlet 52 and the pipe 14.

It will be understood that the valve 40 is identical with the valve 41, though it is disposed in an inverted position relative to the valve 41. The valve 40 has a bell crank lever 71 that is connected to a cable 83.

The cables 80 and 83 extend into the vaporizer housing 12 and around suitable pulleys 84 and 85. The cable 83, at its upper end, has a hook 86 that may be engaged in a loop on a fuse connector 87. The other end of the fuse connector is connected by an eye 88 to the cable 80.

The cables are of such length that, when the hook 86 is engaged with the fuse 87, as shown in Fig. 2, both of the bell cranks will be rocked outwardly, so that they will depress the buttons 14 of the valves and cause the valves to remain open, permitting flow of both liquid and gas.

The housing 12 will be provided with a door 90, shown in Fig. 1, which may be opened only by a suitable key. This door is disposed opposite the fuse 87. When it is desired manually to close the valves for any purpose whatsoever, the door 90 is unlocked and opened, giving access to the hook 86. When the hook 86 is removed from its link on the fuse 87, both valves may be closed by the simple operation of releasing the ends of their cables. The release of tension on the two cables, of course, permits the valves to close by the action of their coil springs 65.

In the event of fire or other excessive heating of the housing 12, the fuse link 87 will break, it being composed of some material that weakens or melts upon being subjected to temperatures above predetermined values. Of course, when the fuse link 87 breaks, the two cables 80 and 83 are released in a manner just as if the hook 86 were removed. This breaking of the link 87 takes place automatically and causes the valves both to close instantly in response to the excess temperature conditions. As a result, the danger due to flame is eliminated.

It will be seen that this construction provides a safety arrangement that takes care of all of the dangerous conditions, and yet does not provide the additional hazard of inadvertent operation. In the first place, it cannot be operated manually except by intention, because it is enclosed within the housing 12. Yet it will operate automatically in the event of excess temperature. Furthermore, both of the valves are closed simultaneously, although either one may be manually opened separately.

What is claimed is:

1. In a mechanism of the kind described, a vaporizer chamber adapted to be operatively associated with a supply tank of vaporizable liquid, passage means entering the vaporizer chamber and adapted to establish communication with the tank for fluid flow between the tank and the chamber, a valve to regulate the flow through said passage, a housing open to the atmosphere disposed about the chamber, a door to the housing, and operating means for the valve responsive to the temperature within said housing, said operating means being in the housing and accessible only by opening of the door.

2. In a mechanism of the kind described, a vaporizer chamber adapted to be operatively associated with a supply tank of vaporizable liquid, liquid passage means entering the chamber and

connectable with the tank to establish liquid flow from the tank to the chamber, vapor passage means entering the chamber and connectable with the tank above its liquid level to establish vapor flow between the tank and the chamber, a valve in each passage means, operating means for said valves, and a common releasable connector for said operating means to hold each valve in one of its positions, whereby when the connector is released both valves may be moved to another position.

3. In a mechanism of the kind described, a vaporizer chamber adapted to be operatively associated with a supply tank of vaporizable liquid, liquid passage means entering the chamber and connectable with the tank to establish liquid flow from the tank to the chamber, vapor passage means entering the chamber and connectable with the tank above its liquid level to establish vapor flow between the tank and the chamber, a valve in each passage means, operating means for said valves, and a common connector for said operating means to hold each valve in one of its positions, said common connector including a frangible, temperature-responsive link, whereby upon excessive temperature conditions the connector is broken and both valves may be operated to their other positions.

4. In a mechanism of the kind described, a vaporizer chamber adapted to be operatively associated with a supply tank of vaporizable liquid, liquid passage means entering the chamber and connectable with the tank to establish liquid flow from the tank to the chamber, vapor passage means entering the chamber and connectable with the tank above its liquid level to establish vapor flow between the tank and the chamber, a valve in each passage means, operating means for said valves, and a common connector for said operating means to hold each valve in one of its positions, a housing for said chamber, the connector extending into said housing, a severing means in the connector within the housing, and securable door means into the housing adjacent the severing means.

5. In a mechanism of the kind described, a vaporizer chamber, a housing open to the atmosphere around the chamber, a passage connected to the chamber and adapted to be connected with a supply tank, valve means for controlling the flow of fluid in said passage, means for holding said valve open, and means within the housing of the vaporizer chamber for automatically or manually releasing the valve to closed position.

6. In a mechanism of the kind described, a vaporizer chamber, a housing around the chamber open to the atmosphere, a passage connected to the chamber and adapted to be connected with a supply tank, valve means for controlling the flow of fluid in said passage, means for holding said valve open, and means within the housing of the vaporizer chamber for releasing the valve to closed position, said last named means including a releasable device normally holding the valve open, but automatically operable to close the valve upon existence of predetermined physical conditions within the housing and prevent the flow of fluid in said passage.

7. In a mechanism of the kind described, a vaporizer chamber, a housing around the chamber open to the atmosphere, a passage connected to the chamber and adapted to be connected with a supply tank, valve means for controlling the flow of fluid in said passage, means for holding said valve open, and means within the housing of

the vaporizer chamber for manually or automatically releasing the valve to closed position, said last named means including a temperature-responsive fuse adapted to automatically release the valve to closed position upon existence of a predetermined temperature within the housing and prevent the flow of fluid in said passage.

8. In a vaporizer system for liquid petroleum fuel, a vaporizer column for connection with a liquid fuel supply tank, a vapor tube entering the top of the column and adapted to be connected to the top of the tank, a liquid tube connecting with the bottom of the column and adapted to be connected to the bottom of the tank, a cut-off valve in the vapor tube, and a cut-off valve in the liquid tube, each of said valves being normally urged toward closed position, means for holding the valves in open position, said last named means being releasable to permit both valves to close simultaneously.

9. In a vaporizer system for liquid petroleum fuel, a vaporizer column for connection with a liquid fuel supply tank, a vapor tube entering the top of the column and adapted to be connected to the top of the tank, a liquid tube connecting with the bottom of the column and adapted to be connected to the bottom of the tank, a cut-off valve in the vapor tube, and a cut-off valve in the liquid tube, each of said valves being normally urged toward closed position, means for holding the valves in open position, said last named means including a mechanical tension connector between the two valves, a housing around the vaporizer column, a door means to said housing, said mechanical connector extending into said housing and having separation means disposed adjacent the door means, whereby when the door is intentionally opened the connector may be separated and the valves moved toward closed position.

10. In a vaporizer system for liquid petroleum fuel, a vaporizer column for connection with a liquid fuel supply tank, a vapor tube entering the top of the column and adapted to be connected to the top of the tank, a liquid tube connecting with the bottom of the column and adapted to be connected to the bottom of the tank, a cut-off valve in the vapor tube, and a cut-off valve in the liquid tube, each of said valves being normally urged toward closed position, means for holding the valves in open position, said last named means comprising a mechanical connector between the

5 two valves, a housing enclosing the vaporizer column, said connector extending into the housing, and said connector including a temperature-responsive link adapted to break upon existence of a predetermined temperature within the housing.

11. In a vaporizer for liquid petroleum fuel, or the like, a vaporizer column, tubular connections connected into the column and adapted to be 10 connected with a supply of liquid fuel, a housing enclosing the column, a valve in the liquid line, and means automatically to effect closure of the valve when the temperature within the housing exceeds a predetermined value.

15. 12. In a device of the type described, a vaporizer chamber associated with a supply tank for vaporizable liquid; a housing disposed about the chamber and spaced therefrom; liquid passage means between the chamber and the tank; vapor 20 passage means between the chamber and the tank; a valve in each passage means; and means for automatically and simultaneously actuating said valves to close the passages when the temperature within the housing exceeds a predetermined amount.

13. In a device of the type described, a vaporizer chamber associated with a supply tank for vaporizable liquid; a housing disposed about the chamber and spaced therefrom; liquid passage means between the chamber and the tank; vapor passage means between the chamber and the tank; a valve in each passage means; yieldable means biasing the valves toward the closed position; and common means for maintaining 35 the valves in an open position against the action of the yieldable means, said maintaining means being automatically released when the temperature within the housing exceeds a predetermined amount so as to simultaneously close 40 both passages.
